WELL LOGGING

Pernell J. Moore, Houston, Tex., assignor to National Lead Company, New York, N. Y., a corporation of New Jersey

Application October 12, 1954, Serial No. 461,857

4 Claims. (Cl. 23—230)

This invention relates to the logging of wells during drilling, more particularly by examination of the mud returns, and relates to an improvement of such mud returns logging.

For some years, it has been common during the drilling of wells for oil and gas by the rotary process, wherein a circulating mud fluid is employed to flush out the cuttings and maintain proper pressure relationships in the hole, to examine the mud return systematically, substantially continuously, and by various techniques, to establish the presence of oil or gas in the returning mud. When this information is coupled with information as to the depth of the formation from which hydrocarbon inclusions in the mud arose, which may be gained from a knowledge of the bit depth, rate of penetration, and mud circulation, then the necessary data are at hand to permit the construction of a log of hydrocarbons, viz., oil and gas, as a function of depth, so as to show the nature of the terrain which has been traversed. General principles are set forth, for example, in Hayward Patent No. 2,214,674.

One of the important hydrocarbon constituents of drilling mud which is detected in well logging procedures of the type described is gas, which is to say, the gaseous constituents of the drilling mud as removed therefrom, for example, by a gas trap such as shown in Wilson et al. Patent No. 2,341,169, and detected as containing combustible constituents by a hot wire gas detector of the known type.

The hot wire gas detector, as is well-known, operates on the principle of catalytic combustion of combustible gases in the presence of air at the surface of a heated catalytic filament which is generally of platinum. The filament is maintained at a temperature high enough to cause catalytic combustion of the gas to be determined or detected by passing an electric current through the filament. If combustion does take place, which will naturally be at the exposed surface of the platinum filament, then the heat liberated by such combustion raises the temperature of the filament, and since platinum has a substantial temperature coefficient of resistance, the detection of such a combustion process can be readily accomplished by following the change in resistance of the filament, which can be done by including it in a Wheatstone bridge circuit. It has been found that methane requires a substantially higher filament temperature for combustion than gases higher in the hydrocarbon series, such as ethane, propane, butane, and so forth, and it has become common practice to get indications at two filament temperatures, generally achieved by subjecting the filaments to two different voltages, one at a fairly high voltage, sufficiently high to oxidize methane, and one substantially lower, so that methane remains unoxidized, whereas the remaining hydrocarbons or other combustible constituents are oxidized in the usual fashion. By taking the difference of the two readings or indications, a measure of the presence of what is

2

nominally methane is obtained, which is of importance in evaluating the nature of the strata traversed since the presence of methane may be an indication of the presence of petroleum.

5 In gas detection in drilling mud, of the type which has been described hereinabove, the results obtained have often been anomalous and unexplainable in terms of the known theories applied. For example, one would normally expect a higher indication when the filament is 10 operated at the higher voltage than would be obtained at the lower voltage, because methane combusted would always be in addition to the other gases present. However, the difference is often in the opposite direction, which would normally be interpreted as a negative methane content, which of course has no correspondence with anything factual. Other anomalous showings have been observed; for example, often when the alkalinity of the drilling mud was reduced, what appeared to be a gas show would be encountered, but it would disappear if the mud alkalinity were raised again. Again, when drilling out cement through a drillable plug, a show of gas has often been observed and many times under stratigraphic conditions which would scarcely admit of the presence of hydrocarbon gases.

20 25 An object of the present invention is to improve the reliability of hydrocarbon detection in drilling muds.

Another object of the invention is to obtain more certain indication of the presence of methane in a drilling mud by differential indications obtained by the use 30 of a hot wire gas detector on the gas derived therefrom.

Another object of the invention is to eliminate the false show of gas generally encountered when drilling a drillable cement plug.

35 Another object of the invention is to make a gas showing observed substantially independent of the alkalinity or pH of the drilling mud.

Other objects of the invention will appear as the description thereof proceeds.

40 45 In the drawings, Fig. 1 shows gas detection logs against depth taken with and without the use of my invention.

Fig. 2 shows a piece of apparatus useful in employing my invention while Fig. 3 shows a detail therein.

Fig. 4 shows a cross-section taken across the middle 50 of Fig. 2.

In accordance with my invention, steps are taken to remove hydrogen from the gas taken from the drilling mud prior to its testing by means of the hot wire detection apparatus. I have found that this eliminates most if 55 not all of the anomalous effects which have just been described, and permits, for example, drilling through drillable cement plugs without the false show of gas generally obtained, and permits operating with a drilling mud at a considerably reduced alkalinity, or a pH in particular below 9, without a more or less continuous, randomly variable gas showing appearing in the indicator.

While there are many ways of removing hydrogen from a gas, and standard texts on gas analysis may be 60 consulted in this connection, I prefer to pass the gas mixture obtained from the drilling mud through a chamber containing a catalyst of the type which oxidizes hydrogen to water, but does not oxidize saturated hydrocarbons of the methane series at the temperature at 65 which the catalyst is maintained. A suitable chamber is shown in Fig. 2, wherein 10 is a brass block drilled to receive a thermostat 12 and heater 13, and also drilled and tapped to receive tubulations 14 and 15 and a supply of catalyst 16. A detail of one of the tubulations is 70 shown in Fig. 3, from which it will be apparent that this part has a threaded portion 17 and a perforated portion

18, so that gas may readily permeate that end of the tube which is within the brass block 11.

As a catalyst, I have found platinum black deposited on the exterior surface of an inert carrier such as porcelain cylinders about 3 mm. in diameter and 3 mm. high, to be suitable. Palladium, especially in the finely divided form of palladium black, is also suitable, and in general is preferred. An effective catalyst can be made, for example, by soaking granules of activated alumina in a dilute, approximately $\frac{1}{2}\%$, solution of palladium chloride, after which the granules are dried under a heat lamp. With the dried alumina granules still hot a stream of hydrogen is passed over them to reduce the palladium chloride to finely divided palladium metal. Palladium catalysts of this type are commercially available such as "Catalyst 'D'" from Baker and Company, and "0.5% palladium on $\frac{1}{8}$ inch activated alumina pellets," from the J. Bishop and Company Platinum Works. A particular advantage of palladium as a catalyst is that a relatively low temperature of about 100° C. is suitable for oxidizing hydrogen without oxidizing saturated hydrocarbons. Cupric oxide can also be used, at a temperature of about 300° C. In connection with the use of palladium, it should be noted that unsaturated hydrocarbons such as ethylene or propylene may combust at low temperatures approaching those used for hydrogen combustion. However, that is generally of no consequence since such unsaturated hydrocarbons do not normally occur in the gas fraction of natural petroleum. They may be introduced into the mud stream artificially, as when light diesel oil is used to form an emulsion mud; but then of course their presence may be readily accounted for.

Returning to the device shown in Fig. 2, the gas-air mixture obtained from the drilling mud is passed into tube 14, past the catalyst 16 maintained at a suitable temperature so that hydrogen will be oxidized and hydrocarbons will not, through the tube 15 and finally through the hot wire gas detector.

It will be understood, however, that any method of eliminating hydrogen from a gas mixture may be used, except that it should not be of active enough nature to cause oxidation or combustion of the other constituents of the gas mixture, particularly the hydrocarbons, which as explained are the saturated hydrocarbons of the methane series. Broadly speaking, therefore, I provide a catalyst which is active enough under the conditions employed to convert hydrogen to water without oxidizing or otherwise changing saturated hydrocarbons all in the presence of air. Specific hydrogen absorbents may of course also be utilized.

An example of the great utility of my process appears in Fig. 1. This is a composite log against depth of a portion of a well drilled for oil, in which the depth figures are shown in column 3 of the figure. Reference numeral 1 of Fig. 1 shows the log of percent sand in cuttings, and reference numeral 2 indicates the curve showing the drilling rate in feet per hour at which the successive strata were drilled. Reference numeral 7 shows the log of the meter reading of total gas obtained by the use of a hot wire detector on the gas taken from the drilling mud in the manner described, but without the use of the present invention. In other words, in obtaining the curve 7, the detecting filament was operated at a temperature high enough to combust all of the hydrocarbons including methane and therefore high enough to combust hydrogen gas. The curve indicated by 6 is the difference curve corresponding to methane, obtained by operating the filament at the lower temperature described hereinabove, so that all hydrocarbons and hydrogen, if any, except methane would be combusted. In those portions of curve 6 where the indicated reading is zero, for the most part a negative difference was obtained, which resulted from the presence of hydrogen as described hereinabove, although the negative reading differences

were not plotted as such since, as has been pointed out, a negative quantity of methane has no physical meaning.

Curve 5 of Fig. 1 shows the total gas reading obtained after hydrogen had been removed by means of a palladium black catalyst operated at about 100° C. in the manner described. Curve 4 is the corresponding methane curve, obtained by operating the detecting filament at a lower temperature and subtracting the two readings.

Comparison of curves 6 and 7 on the one hand, with 10 4 and 5 on the other reveals some startling differences. In the first place the total gas curve 7 has several times the absolute magnitude of the total gas curve 5 throughout the entire gas portion log. The reason for this, of course, is that hydrogen was present in the mud during the period shown, and contributed heavily, and in fact overwhelmingly, to the gas detector filament reading. However, this curve is practically meaningless for the purposes at hand, since the well was drilled in search of hydrocarbons instead of hydrogen, in which the latter undoubtedly arose adventitiously from corrosion of steel during the drilling operations or the like. The second observation which may be made is that the large amount of hydrogen present masked the methane completely except where the methane content was very high. Curve 6 shows only the high peaks of curve 4, and all of the highly significant details for strata indicating medium and low amounts of methane is missing from curve 6. On the other hand, curves 4 and 5 are diagnostic of the strata penetrated, and the slight difference between curves 20 25 30 35 4 and 5 at all depths indicates that the gas present was largely methane, which is exactly opposite to the conclusion which would be erroneously drawn from a comparison of curves 6 and 7. The advantages of the invention, therefore, in presenting an accurate and useful picture of the hydrocarbons present are immediately apparent from the above.

It will be noted from the description and examples given of the invention that new and highly useful results are obtained thereby. It is therefore to be understood that the invention is a broad one and although specific embodiments have been described, such modifications as may be made by the broad scope of the invention and the claims appended hereto are intended to be included herein.

What I claim is:

1. The method of logging a well drilled with the aid of circulated drilling mud fluid for the determination of certain hydrocarbon content which may include saturated hydrocarbons, wherein a portion of any gas entrained in the mud fluid issuing from the well is continuously removed, admixed with a substantial quantity of air, tested for the presence of saturated hydrocarbons by burning in contact with an electrically heated catalytic wire wherein measured changes of resistance of said wire are an indication of the quantity of hydrocarbon burned, the step of eliminating inaccuracy of indication by removing the hydrogen prior to the said catalytic burning by passing the gas-air mixture over a catalyst consisting essentially of palladium on an inert carrier, and maintaining said catalyst at a temperature high enough to combust hydrogen but too low to combust saturated hydrocarbons.

2. The method of logging a well drilled with the aid of circulated drilling mud fluid for the determination of the content of certain saturated hydrocarbons, wherein at least a portion of any gas entrained in the mud fluid issuing from the well is continuously removed, admixed with sufficient quantity of air to support the combustion of any inflammable gases in the mixture, tested for quantity of saturated hydrocarbons by burning said hydrocarbons by and in contact with an electrically heated catalytic wire wherein measured changes of resistance of said wire are an indication of the relative quantity of hydrocarbons burned, the step of eliminating erroneous indications resulting from the presence of hydrogen in the gas mixture by removing the hydrogen prior to said catalytic burning by passing the whole portion of the air-gas

mixture over a catalyst consisting essentially of palladium on an inert carrier, and maintaining said catalyst at a temperature high enough to combust hydrogen and unsaturated hydrocarbons present but too low to combust saturated hydrocarbons.

3. The method of logging a well drilled with the aid of circulated drilling mud fluid for the determination of the content of certain saturated hydrocarbons of the methane series, wherein at least a portion of any gas entrained in the mud fluid issuing from the well is continuously removed, admixed with a sufficient quantity of air to support the combustion of any inflammable gases in the mixture, passed over a catalytic wire heated at one time to a temperature to burn all but the methane and at another to a temperature to burn all hydrocarbons therein, wherein measured changes of resistance of said wire are an indication of the relative quantity of hydrocarbon burned at each time and difference in quantities is representative

of the methane content, the step of eliminating erroneous hydrocarbon quantity indication resulting from the presence of hydrogen in the gas mixture by removing the hydrogen prior to said catalytic burnings.

5. 4. The method defined in claim 3 in which the said step includes the removal of unsaturated hydrocarbons along with the hydrogen.
